UNITED STATES PATENT OFFICE.

HENRY G. ECKSTEIN, OF CHICAGO, ILLINOIS, ASSIGNOR, BY MESNE ASSIGNMENTS, TO THE CRACKER JACK CO., A CORPORATION OF ILLINOIS.

MANUFACTURE OF MOISTUREPROOF PACKAGES.

Application filed September 26, 1919. Serial No. 326,551.

To all whom it may concern:

Be it known that I, HENRY G. ECKSTEIN, a citizen of the United States, and a resident of Chicago, county of Cook, and State 5 of Illinois, have invented certain new and useful Improvements in the Manufacture of Moistureproof Packages, of which the following is a specification.

The invention relates to the manufacture 10 of waxed paper packages for marketing candies, pop-corn confection and other material readily affected by the absorption of moisture.

A paper package or wrapper containing 15 wax only in its fibrous body or having only a slight coat or film of wax which is easily cracked or broken, or leaves the fibres of the paper exposed, will not effectively prevent the passage of water vapor, but, for 20 efficient protection, the package must have a substantial, unbroken film or coat of wax extending throughout all portions thereof including its folds or joints.

The present invention seeks to provide at 25 low cost a waxed paper package which is vapor-proof at all points. In accordance therewith, the goods are first enclosed in an inner wrapper or package, which is preferably in the form of a box or carton of relatively stiff paper board and suitable for containing loose or granular material such as candies, pop-corn confection, or the like. The filled inner package is then enfolded in a flexible waxed paper sheet or wrapper and 35 the overlapping side and end folds are securely sealed at all points through the medium of wax on the sheet by applying heat and pressure to the folds. The package, thus wrapped and sealed, is then immersed 40 in a bath of melted paraffin wax, drained and cooled to form a substantial, continuous, uniform coat or film over all portions of the package.

In the accompanying drawing, which illustrates the form of package to which the 45 invention is particularly directed, Figure 1 is a perspective view of the inner package or carton. Fig. 2 is a perspective view of the finished package; and, Fig. 3 is a detail 50 section thereof.

The inner wrapper or package containing 55 the goods and which is to be rendered vapor-proof, should be of regular form and present smooth, comparatively rigid surfaces to serve as a suitable support or form over

which the flexible waxed sheet or wrapper can be readily folded and securely sealed. Preferably, as stated, the inner wrapper or carton is formed of stiff paper box-board and comprises a rectangular body 1 having 60 end flaps 2 which are folded inwardly to enclose the contained goods.

The sealing wrapper 3 comprises a sheet of medium weight paper which is flexible and can be readily folded and which is heavily waxed. Preferably manila or bleached sulphite paper weighing from twenty to thirty-five pounds per standard ream before waxing is employed and the paper carries sufficient paraffin wax, say from ten 70 to thirty pounds per ream, to provide a heavy surface coat of wax on both sides of the sheet in addition to the wax in its body, so that all portions of the folds of the wrapper can be readily and efficiently sealed by 75 the application of heat and pressure. The waxed sealing wrapper is folded about the inner filled package to completely enclose the same, and the overlapping side and end folds 4 and 5 of the wrapper are heated to 80 partially melt the wax coat and are pressed into snug contact until the melted wax is cooled and set to seal the folds.

The wrapped and sealed package is then 85 dipped in a bath of melted paraffin for a few seconds. After removal from the bath, excess wax is allowed to drain from the package and it is cooled by exposure to the air or to a cooling air blast to set the wax and form a uniform, continuous film over all portions 90 of the package. Paraffin wax having a melting point of about 128° or 130° F. is preferably employed and the bath should be maintained at a temperature of about 150° to 160° F., care being taken that the temperature be high enough to insure proper drainage of the packages after removal from the bath and also to avoid excessive temperatures which would tend to open the sealed folds of the packages.

By dipping the package as described, a coat or film to the extent of about 1½ to 2½ pounds per 100 square feet will be added, and, since the package has been previously enfolded and tightly sealed in a paraffined 105 wrapper having a surface coat, the added wax cannot penetrate or be absorbed by the walls of the package or seep in through its folds or joints. Nor will it form a film which can be readily broken or chipped off. 110

Instead the additional wax will firmly unite or become fused or bonded with the wax already on the surface of the wrapper to form a heavy superficial coat which will seal up all minute cracks and imperfections in the sealing wrapper and cover any portion of its film which may have been impaired by the heating and sealing of the folds. Furthermore, where a previously waxed wrapper is employed, the amount of wax added by dipping can be more readily controlled and more effectively and economically employed to provide a uniform film or coat than would be possible if an unwaxed, glued or pasted wrapper were used. In Fig. 3 of the drawing the black line 6 indicates the wax coat on the inner surface and between the folds of the wrapper and the heavier line 7 is intended to indicate the film formed by its outer coat and the wax added thereto by the dipping operation and which extends over the entire surface of the package, including the side and end folds.

The folding, sealing and dipping operations may be carried out in various ways, but preferably by suitable machinery. In dipping, the entire package is preferably immersed, but if the wrapper is originally provided with a heavy surface coat or film on both sides, good results can be obtained by dipping the end portions only to thereby thoroughly protect the end folds.

When the package is withdrawn from the bath of melted paraffin, excess wax is drained off, as stated, preferably by holding the package for several seconds in such a tipped or inclined position that one corner point thereof is lowermost. In this way, the excess wax readily collects and falls from the lowermost corner point of the package and thus aids in effecting the uniform disposition of the added wax. Usually, to protect the finished package from injury, it will be inclosed in an outer pasted wrapper of heavy paper or paper board.

The details set forth may be varied without departure from the essentials of the invention as defined in the claims.

I claim as my invention:

1. The method of vapor-proofing packages which consists in enfolding the goods in a flexible waxed paper wrapper the wax on which may at times be partially destroyed in the operation of sealing the package, then applying heat and pressure to the overlapping folds of the wrapper to seal the same by the wax thereon, and subsequently restoring a film of wax to any such denuded surfaces of the wrapper to provide a substantial, continuous film over all portions of the package.

2. The method of forming filled vapor-

proof packages which consists in enclosing the goods in an inner wrapper to form an inner package of regular form and having smooth, substantially rigid sides and ends, enfolding the same in a flexible paper wrapper heavily coated with wax, the wax on which may at times be partially destroyed in the operation of sealing the package, applying heat and pressure to the sides and end folds of the wrapper to seal the same by the contained wax and subsequently immersing the package in melted wax and draining and cooling the same to provide a substantial, continuous film over all portions of the package, substantially as described.

3. The method of forming a vapor-proof package which consists in enclosing the goods in a box of stiff material, and enfolding the same in a heavily waxed paper wrapper the wax on which may at times be partially destroyed in the operation of sealing the package, then applying heat and pressure to the side and end folds of said wrapper to seal the same by the contained wax, and subsequently dipping the package in melted wax to provide a substantial, continuous film over all portions of the package, substantially as described.

4. The method of vapor-proofing packages which consists in enclosing the contents in a foldable wrapper having a surface film of wax enclosing the paper against the entrance of moisture to the body of the paper but which film may at times be partially destroyed in the operation of sealing the package, then applying heat and pressure to the overlapping folds of the wrapper to melt the wax thereon and seal the same therewith, and dipping the package in melted wax to re-film any portion of the surface from which the wax may have been displaced in the operation of sealing.

5. The method of forming filled vapor-proof packages which consists in enclosing the contents to form an inner package, enclosing said inner package in an outer wrapper of foldable paper having a surface film of wax sealing such outer wrapper against the entrance of moisture to the body of the paper composing the same but which film may at times become partially destroyed in the operation of sealing its overlapping folds, then applying heat and pressure to the overlapping folds of said last referred to wrapper to melt the wax thereon and seal the same therewith, and dipping the package in melted wax to re-film any portion of the surface of such outer wrapper from which the wax may have been displaced in the operation of sealing.

HENRY G. ECKSTEIN.
